[57] CLAIM

The ornamental design for a front squeeze trigger for a fire extinguisher, as shown and described.

DESCRIPTION

FIG. 1 is a perspective view of a front squeeze trigger for a fire extinguisher showing our new design;

FIG. 2 is a top plan view thereof;

FIG. 3 is a front elevational view thereof;

FIG. 4 is a right side elevational view thereof;

FIG. 5 is a rear elevational view thereof; and,

FIG. 6 is a left side elevational view thereof.

The fire extinguisher bottle is shown in broken lines in FIGS. 1, 3-6 for illustrative purposes only and forms no part of the claimed design.
